BOTTLE CAPPER

Filed Oct. 9, 1930

UNITED STATES PATENT OFFICE

JOHN J. BALAUN, OF CANTON, OHIO

BOTTLE CAPPER

Application filed October 9, 1930. Serial No. 487,482.

The invention relates to devices for placing crimped metal caps upon bottles.

The object of the improvement is to provide a bottle capper arranged to be instantly adjusted to accommodate bottles of varying heights and so constructed that when adjusted to any particular sized bottle, any desired number of bottles of that size may be capped without further adjustment of the device.

10 Another object is to provide means for adjusting the pressure to be applied to the bottle cap in operating the device.

A still further object is to provide means for holding the operating handle in raised 15 position to permit ready adjustment of the plunger to accommodate bottles of various heights.

The above and other objects may be attained by constructing the device in the manner illustrated in the accompanying drawing, in which

Figure 1 is a side elevation partly in section showing the operating handle in raised position;

25 Fig. 2 a similar view showing the handle partly lowered with the plunger just contacting with the cap of a bottle;

Fig. 3, a similar view showing the handle in lowered position; and

30 Fig. 4, a fragmentary elevation of the spring catch for holding the handle in raised position.

Similar numerals refer to similar parts throughout the drawing.

35 The improved bottle capper may include a base or table 10 having an upright 11 preferably formed integrally therewith as by casting or the like.

Feet 12 may be downturned from the base 40 for contact with a table, bench or the like upon which the device may be supported and if desired, the base may be provided with apertures 13 through which screws or other fastening devices may be located for permanently securing the same to the bench or other support.

A cushion 14, which may be formed of leather or other suitable material, may be fixed upon the base 10 to receive the bottle 50 to be capped and is preferably provided with

a rim flange 15 to assist in properly centering the bottle.

The upper end of the upright 11 is curved as at 16 and terminates in a vertical bearing portion 17 located above the center of the cushion 14.

55 A plunger 18 is slidably mounted through the bearing 17 and provided at its lower end with the inverted cup 19 for crimping the usual cap 20 upon the neck of the bottle 21, a cushion 22 of rubber or the like being carried within the cup 19 for contact with the top of the cap.

A operating handle or lever 23 is pivoted upon a lug 24 formed at the lower end of the bearing portion 17, as by the pin 25, and has a handle grip 26 of any usual construction upon its free end.

Means for operatively connecting the handle 23 to the clamping head 30 preferably 70 includes a pair of links 27 which are pivoted at their lower ends, as at 28 to the handle 23 adjacent to the lower end thereof, the upper ends of said links being pivotally connected as at 29 to the clamping head 30 which is 75 provided with an opening 31 slightly larger in diameter than the plunger 18.

A collar 32 may be fixed upon the upper portion of the plunger 18 as by a screw 33 for limiting the downward movement of the plunger relative to the clamping head and washers 34 of leather or the like are preferably located beneath said collar for contact with the clamping head, forming a cushion to absorb shock.

85 A lug 35 is formed at one side of the bearing member 17 and has slidably mounted therethrough an adjusting screw 36 provided with a coil spring 37 located between the head 38 of the screw and the lug 35.

90 A spring catch 39 is connected to one of the links 27 as by a screw 40 and adapted to be engaged by the handle 23, when in the raised position, to hold the handle in this position as shown in Fig. 1.

95 For the purpose of limiting the upward movement of the handle 23, a stop pin 41 may be provided upon the inner side of one of the links 27 for engagement with the handle.

It will be seen that when the handle is raised sufficiently to raise the clamping head 30 out of contact with the bolt 36, the free end of the clamping head will tilt downward by its own weight, as shown in Fig. 1, the plunger 18 being wedge clamped in the aperture 31 as illustrated in said figure.

With the parts in this position the plunger may be raised to adjust the position of the same for capping a bottle of any desired height, and will easily slide upward through the head 30 but the plunger cannot be pushed downward through the head in this position.

After the plunger has been properly positioned, the handle is moved downward, sliding the plunger downward through the bearing 17 and engaging the cap 20 which has been placed upon the neck of the bottle, by the cup 19.

As the cushion 22 of the cup contacts with the cap of the bottle, the free end of the clamping head 30 will contact with the upper end of the adjusting screw 36 and as the handle 23 continues to move downward, the links 27 will instantly pull the head into substantially horizontal position, when for an instant the plunger is free to move within the head.

At this point, however, the plunger cannot move as it is supported upon the cap of the bottle, as shown in Fig. 2. Further downward movement of the handle 23 will tilt the head downward from its free end as shown in Fig. 3, again clamping the plunger, this time in such a manner that the plunger cannot be pushed upward through the head.

As the handle moves down to its lower position as shown in Fig. 3, the head will carry the plunger downward, compressing the cushion 22 in the cup 19 and tightly clamping the cap 20 upon the neck of the bottle.

It will be seen that in this position the spring 37 upon the bolt 38 will be compressed by the downward movement of the head, holding the head in clamping position upon the plunger.

The tension upon the spring 37 may be adjusted by adjusting the bolt 38 by means of the nut 38a at the lower end thereof, thus providing for the amount of pressure to be applied to the cap in clamping the same.

After the plunger has been set for a bottle of any desired height, any number of bottles of the same height may be successively capped without changing the adjustment on the plunger as it will be seen that in the upward movement of the handle, after each cap has been properly crimped upon the bottle, the head will first pass over the position shown in Fig. 2 and again clamp the plunger in the manner shown in Fig. 1 before the plunger is raised out of contact with the bottle cap, thus permitting further upward movement of the handle to move the plunger

with it back to the original starting position.

Adjustment of the plunger may be easily made for any desired height of bottle capable of being capped upon a device of the size provided by simply slidably moving the plunger relative to the clamping head and then raising the plunger to starting position by means of the handle 23 and it will also be seen that the pressure applied to cap the bottles may be controlled by adjusting the nut 38a upon the screw 38.

I claim:

1. A bottle capper including a bearing portion, a plunger slidably mounted through said bearing portion, a clamping head through which the plunger is located, means for raising and lowering the clamping head, and means for releasing the plunger from the clamping head at a predetermined point, and for instantly reclamping the plunger in the head.

2. A bottle capper including a bearing portion, a plunger slidably mounted through said bearing portion, a clamping head through which the plunger is located, means for raising and lowering the clamping head, and a spring pressed member for releasing the plunger from the clamping head at a predetermined point and for instantly reclamping the plunger in the head.

3. A bottle capper including a bearing portion, a plunger slidably mounted through the bearing portion, a clamping head provided with an opening slightly larger than the plunger, through which the plunger is located, means for normally tilting the clamping head to clamp the plunger therein, and lever means operatively connected with the clamping head for raising and lowering the plunger.

4. A bottle capper including a bearing portion, a plunger slidably mounted through the bearing portion, a clamping head provided with an opening slightly larger than the plunger, through which the plunger is located, means for normally tilting the clamping head to clamp the plunger therein, and means for tilting the head in the opposite direction at a predetermined point to instantaneously release the plunger and reclamp it in the head.

5. A bottle capper including a bearing portion, a plunger slidably mounted through the bearing portion, a clamping head provided with an opening slightly larger than the plunger, through which the plunger is located, means for normally tilting the clamping head to clamp the plunger therein, and a spring pressed member for tilting the head in the opposite direction at a predetermined point to instantaneously release the plunger and reclamp it in the head.

6. A bottle capper including a bearing portion, a plunger slidably mounted through said bearing portion, a clamping head through

which the plunger is located, the plunger being free to move relative to the clamping head in one position of the head, lever means operatively connected with the clamping head for raising and lowering the plunger, and means for moving the clamping head from clamping to releasing position when the plunger is lowered to a predetermined position.

10 7. A bottle capper including a base having an upright, a bearing portion in the upright, a plunger slidably located through the bearing portion, a clamping head having an aperture formed therein slightly larger
15 than the plunger through which the plunger is located, a lever pivotally connected at one end to the upright, a link pivotally connected between the lever and one end of the clamping head, and spring pressed means on the upright for contacting with the other end of the clamping head for tilting the head when the plunger is lowered beyond a predetermined position.

20 In testimony that I claim the above, I have
25 hereunto subscribed my name.

JOHN J. BALAUN.
